UNITED STATES PATENT OFFICE.

ALBERT D. SANDERS, JR., OF EVANSTON, ILLINOIS, ASSIGNOR TO BENJAMIN ELECTRIC MANUFACTURING COMPANY, OF CHICAGO, ILLINOIS, A CORPORATION OF ILLINOIS.

REFRIGERATOR.

Application filed June 15, 1922. Serial No. 568,398.

To all whom it may concern:

Be it known that I, ALBERT D. SANDERS, Jr., a citizen of the United States, residing at Evanston, in the county of Cook and State of Illinois, have invented new and useful Improvements in Refrigerators, of which the following is a full, clear, concise, and exact description, reference being had to the accompanying drawing, forming a part of this specification.

My invention relates to refrigerators and especially to that class of refrigerators designed for home use, and which are provided with side openings which afford easy access to the ice and food compartments.

In the ordinary refrigerator for household use, comparatively long side opening doors are usually arranged to provide access to the food in the interior of the refrigerator, and when these doors are open, the heavy cold air flows out of the bottom part of the opening; while warm air rushes in at the upper part, thus causing considerable loss of cold air while the door is open, and as these doors are open quite frequently in use, the ice is melted very rapidly. In my invention I have successfully overcome this and other objections, and one of the objects of my invention is to provide a convenient means of inserting and removing articles from the food compartment and at the same time to prevent the cold air from flowing out of the refrigerator and the warm air flowing in while the articles are being removed or inserted.

Another object of my invention is to provide a refrigerator having means accessible from the side thereof for the insertion or removal of various articles, the said means being arranged to substantially close the openings in the side of the refrigerator while the articles are being inserted or removed.

Another object of my invention is to provide a refrigerator which will be economical, efficient and durable, and cheap to manufacture.

Further objects will appear from the detailed description to follow and from the appended claims.

50 In the drawings in which an embodiment of my invention is shown—

Figure 1 is a perspective view of my invention, one of the drawers being removed; Fig. 2 is a vertical longitudinal section

taken on a line corresponding to line 2—2 of Fig. 3;

Fig. 3 is a sectional view taken on a line corresponding to line 3—3 of Fig. 2:

Fig. 4 is a perspective view of one of the drawers; and

Fig. 5 is a sectional perspective view through one of the drawer fronts showing the sealing means for preventing the cold air from escaping around the openings or the warm air from entering the refrigerator.

Referring now to the drawings in detail, in my invention, as illustrated, I provide a wooden casing or cabinet 10, having a bottom and side walls, and provided with a top 11 secured thereto, and arranged to be used as a table. A suitable lining 12, preferably of enameled sheet metal, is located within the casing and spaced from the walls thereof, the space between the lining and the walls being filled with a suitable heat-insulating packing 13.

An ice chamber 14, having a bottom 15 and side walls 16, is arranged to contain ice, the bottom 15 being provided with a suitable cold air outlet 17, the ice being supported on a rack 18 spaced from the bottom 15. The side walls 16 are provided with the air inlets 19. The food compartment 20 is arranged around the ice chamber, as illustrated. The ice chamber 14 is provided with a door 21 having the usual refrigerator lock 22. Drawers 23 are arranged in the food compartment as shown, and are inserted through the openings 24, and are also provided with suitable refrigerator locks, as illustrated.

Suitable angle irons 25 are secured to the lining 12 for the purpose of supporting the drawers 23. A drain pipe 26 is provided, extending through the bottom of the refrigerator and connected with the ice chamber in the usual manner.

One of the drawers 23 is illustrated in Figure 4, and is provided with a bottom 27 and side walls 28, formed of a comparatively heavy wire screen, as illustrated, but may be formed of any suitable foraminous material, such as perforated sheet metal. The end 29 of the drawer is preferably made of enameled sheet metal and arranged to close the opening 24 in the casing when the drawer is pulled out until the upwardly extending portion 29^a engages the front of the

refrigerator above the opening 24. The front end 30 of the drawer is made of wood, as illustrated in Figure 5, and is provided with a flange 31, having a suitable gasket 32 secured thereon for the purpose of providing an air tight connection between the drawer front and the casing. A movable partition 33, preferably made of enameled sheet metal, is located in the drawer and 10 supported on the side walls 28, and is arranged to close the drawer opening 24 when the drawer is partially drawn out, and is arranged to be moved to any desired location in the drawer. Strips 34 are secured to 15 the bottom of the drawer, as shown in Figure 4, and are arranged to slide on the angle irons 25 on which the drawer is supported. In this construction, the circulation of cold air in the refrigerator is from the ice 20 chamber downwardly through the opening 17, in the direction of the arrow, then in an upwardly direction through the food compartment 20, around the sides of the ice chamber and through the openings 19 in the 25 side walls 16; the bottom and side walls of the drawers being formed of foraminous material, allow an unobstructed current of air around any of the articles placed in the refrigerator.

30 The drawers may be of different heights to provide room for various articles, such as milk bottles, etc.

In the construction, as illustrated, when a drawer is partially pulled out, the partition 33 substantially closes the opening 24 thereby preventing the loss of any cold air except that contained in the front end of the drawer. When the drawer is pulled out to its limit the end 29 closes the opening 24 35 and thereby prevents any further loss of cold air. The drawer openings 24 are comparatively small and there is no oppor-

tunity, even if one of the drawers is completely removed from the refrigerator, for any great amount of cold air to flow out of the opening and warm air to go in its place.

While I have shown and described a practical form of my invention, it is obvious that it may be embodied in other forms covered and defined by the appended claims.

Having thus described my invention, what I claim as new and desire to secure by Letters Patent of the United States is:—

1. In a refrigerator the combination of a casing having a food chamber and an ice 55 chamber therein, drawers in said food chamber and accessible from the side thereof, said drawers having non-foraminous ends and a movably adjustable partition of non-foraminous material supported in said 60 drawer.

2. A food receptacle for refrigerators having a bottom and side walls formed of foraminous material, ends in said food receptacle formed of non-foraminous material, 65 and a movable partition in said food receptacle formed of non-foraminous material, said partition being removably supported on the side walls of said food receptacle.

3. A food receptacle for refrigerators, the 70 body of said receptacle being formed of wire, and a movable non-foraminous partition in said food receptacle, said food receptacle having non-foraminous ends.

4. A drawer for refrigerators comprising 75 a body portion formed of foraminous material, ends in said drawer formed of non-foraminous material, and a movable partition in said drawer, said partition being 80 formed of non-foraminous material.

In witness whereof, I have hereunto subscribed my name.

A. H. SANDERS, JR.
